UNITED STATES PATENT OFFICE.

MONROE SUNSHINE, OF NEW YORK, N. Y.

SADIRON.

1,317,998.

Specification of Letters Patent.

Patented Oct. 7, 1919.

Application filed March 30, 1917. Serial No. 158,720.

To all whom it may concern:

Be it known that I, MONROE SUNSHINE, a citizen of the United States, residing at New York, in the county of New York and State 5 of New York, have invented certain new and useful Improvements in Sadirons, of which the following is a specification.

My invention relates to sad irons and more particularly to an improved sad iron 10 internally heated by a mixture of gas and air.

One of the objects of my invention is to provide an improved base for sad irons consisting of a hollow body and forming a combined ironing plate and floor plate for the sad iron. The base is cored out to form a hollow structure having air inlet openings at the edges of the base and air outlet openings at or near the center of the part of the 15 base which constitutes the floor plate of the sad iron.

Another object of the invention is to provide an improved form of sad iron in which the handle and the plate which carries it 20 are secured to and insulated from the body of the sad iron in a novel manner.

Another object of the invention is to provide an improved form of hollow body for the sad iron and to provide the rear end of 25 the said hollow body with an improved door through which access may be had to the inside of the body.

Another object of the invention is to provide an improved burner construction for 30 heating the floor plate and ironing plate of the sad iron.

Another object of the invention is to provide a novel and improved means for fastening all of the parts of the sad iron together.

Another object of my invention is to provide an improved gas and air mixing device for the pipe which leads the combustible mixture into the burner of the sad iron.

The above and other objects and the novel 40 features of my invention will be apparent from the following description taken in connection with the accompanying drawings which constitute a part of this application and in which:

Figure 1 is a side elevation of a sad iron embodying my invention;

Fig. 2 is a central longitudinal vertical 45 sectional view of the sad iron embodying my invention taken on the line 2-2 of Fig. 8;

Fig. 3 is a horizontal sectional view of the 50 sad iron, taken on the line 3-3 of Fig. 2;

Figs. 4 and 5 are detail views showing modified forms of the means for holding the door shown in Fig. 11;

Fig. 6 is a plan view of the combined floor 60 plate and ironing plate;

Fig. 7 is a horizontal section taken on a line slightly below the line 7-7 of Fig. 2 showing the interior construction of the combined floor plate and ironing plate; 65

Fig. 8 is a rear end elevation of the sad iron;

Fig. 9 is a view of the door for closing the opening in the rear end of the hollow body of the iron; 70

Fig. 10 is a vertical sectional view of the sad iron taken on the line 10-10 of Fig. 1; and

Fig. 11 is a detail view illustrating the manner of holding the door of the body in 75 position.

Referring to the drawing, A designates the base or combined floor plate and ironing plate of the sad iron, the floor plate constituting the top part 15 of the base A and 80 the ironing plate 16 constituting the lower part of the base A. The bottom part or ironing plate 16 has a rim flange 17 extending entirely around its perimeter and extending above the top side of this plate toward the bottom side of the floor plate 15 and leaving a space or slot 18 between the upper edge of the flange 17 and the lower side of the floor plate 15 for the admission 85 of air into the space between the ironing plate 16 and the floor plate 15. The slot or air inlet opening 18 extends around the sides and rear end or heel of the sad iron and is closed at the front or point where the rim flange 17 is united with the floor 90 plate 15.

The floor plate 15 and the ironing plate 16 are united at intervals by parallel pads or webs 20, which are formed integral with the top and bottom sides of the ironing plate and floor plate, respectively. The pads or webs 20 constitute means for conducting heat from the floor plate of the sad iron to the ironing plate thereof. These heat conducting pads or webs are parallel to one 100 another and spaced apart to leave air passages 21 between them and the inner ends of the heat conducting webs 20 are also spaced apart to leave air passages 22 at the center between the plates 15 and 16. However, two 105 of the webs or pads 20 are united at the center and provided with a recessed opening

to receive the threaded lower end of a post or stud 23 which constitutes a portion of the means for securing the other parts of the sad iron to the base A. The heat conducting pads or webs 20 are joined to the rim flange 17 by integral narrow neck webs 24 so as to form wide mouths 25 at the air inlet passage 18 for the lateral air passages 21.

The floor plate 15 has two rows of rectangular openings 26 therein on opposite sides of the longitudinal center line thereof and directly above the spaces 22 within the hollow base. These apertures or openings 26 are outlets for the air which enters the hollow base through the slot 18 at the margin thereof. The floor plate 15 also has a circular opening 27 therein through which the post 23 passes. This opening 27 also permits the air to pass up into the hollow body 20 of the sad iron. Two parallel walls 28 are formed integral with the upper side of the floor plate 15 and extend upwardly therefrom and also extend along the outer sides of the rows of apertures 26.

A burner B is mounted upon the upper side of the floor plate 15 and consists of a hollow casting which is provided with an opening 281 through which the post 23 extends. The burner B also has a hollow chamber 29 formed by the side walls 30, the bottom wall 31, the rear wall 32 and the top wall or roof 33. The rear wall 32 is provided with a threaded opening 34 to receive the threaded end of a pipe or conduit 35 through which combustible material is delivered to the chamber 29 of the burner. The bottom wall of the burner has two rows of outlets 36, each inside of the lower edge of the side walls 30. These outlets discharge the combustible material on to the top side of the floor 15 and outside of the upwardly extending walls 28 at the sides of the rows of air inlet apertures 26. The walls 28 serve to cause the entering air to issue upwardly from the apertures 26 against the under side of the bottom 31 of the burner and then flow outwardly to supply air for combustion of the gas and air flames issuing from the outlets 36. The burner B tapers forwardly as shown in Fig. 3 and the side walls 30 thereof slant from the upper wall 33 to the lower wall 31. At or near its lateral edges the burner B also has two depending flanges 37 extending downwardly toward the floor 15 to deflect the flame and hot gas against the floor 15. The space beneath the burner and within the depending flanges 37 constitutes a flame chamber open at its base, the flanges 37 serving to deflect the flame against the floor of the sad iron. The opening 281 which accommodates the post 23 is surrounded by a circular wall 282 which prevents communication between the opening 281 and the burner chamber 29.

The front end of the burner B has a

downwardly extending part 38 which forms a leg to support that end of the burner and the rear end of the burner is provided with two legs 39 at opposite sides thereof. The legs 38 and 39 support the burner and serve to locate the flange 37 the required distance above the floor plate 15. The upper end of the post or stud 23 is threaded as shown in Figs. 2 and 10 and is adapted to receive a nut 40, which is adapted to be screwed down on to a washer on the upper side of the roof of the burner to fasten the burner in position within the hollow body H.

The pipe or conduit 35 which leads the combustible mixture to the burner B is threaded at its outer end and carries a gas and air mixing Bunsen device K which has a gas and air passage 41 at the end which is connected to the pipe 35 and a gas passage 42 at the end to which a flexible gas tubing may be connected. The wall of the gas and air passage 41 has a series of air inlets 43 therein, and the two passages 41 and 42 are connected together by a restricted gas passage 44; the end nearest the gas passage 42 terminates in a preferably tapering part 45 extending into the gas passageway 42, thus forming a depression or pocket or trap for impurities between the part 45 and the walls of the gas passageway 42 to prevent the restricted gas passageway 44 from becoming clogged. The construction of the device K provides for a thorough mixture of gas and air for the burner and a means to delay or entirely prevent impurities clogging the restricted passage 44.

The burner B is inclosed by a hollow shell or body H which is open at the top and bottom and also has a cutaway part 46 in one side and at its upper edge to let out the products of combustion at this lateral edge. The sides of the body H slant upwardly and inwardly and approximate the inclination of the outside of the side walls 30 of the burner. The upper side of the floor 15 of the iron has two rim flanges 47 which meet at the point of the sad iron. The upper side of the floor 15 also has two walls 48 within the rim flanges 47 and spaced therefrom to provide wide grooves 49 to receive the lower edges of the sides of the body H and the two walls 48 are for the purpose of conducting heat from the flames of the burner to the floor 15. The rear wall of the body H has an opening 50 therein which is adapted to be closed by a door D. The opening 50 is provided to admit the pipe 35 which supplies the combustible mixture to the burner, and is also provided so that access may be had to the inside of the body H to light the combustible gases at the burner B. The cutaway part 51 of the door is arranged so that the door D may be closed and opened with the pipe 35 in position and without interfering with the latter.

The door D is provided with two hinge pivots 52 formed integral with the opposite lower edges thereof. As shown in Figs. 2 and 3, the hinge pivots 52 are inside the 5 plane of the door and when the door is in position they bear against the inside surface of the rear wall of the body H and are held in place by the legs 39 of the burner B which are spaced away from the inside of the rear 10 wall of the body H to provide recesses to receive the hinge pivots 52. In Figs. 4 and 5 I have shown other ways of holding the hinge pivots 52 of the door in place. In Fig. 4 the floor 151 is provided with bosses or 15 projections 152 integral with its upper side spaced a distance from the rear wall of the body H to provide the recess for receiving the hinge pivots 52. In Fig. 5 the hinge pivots 52 of the door D fit in and are held in place by recesses 153 in the side wall of the body H. In Fig. 11 the legs 39 of the burner B are shown as provided with rearwardly extending projections 391 a distance above the floor 15 to form recesses 392 to receive 20 the pivot pins of the door and hold the latter in place in the door opening 50. The rear side of the door D is provided with a raised part 54 which terminates at its lower end in a knob 55. At the side of the door on 25 the rear wall of the hollow body H there is a latch 56 pivotally connected thereto at 57 and which is adapted to swing downwardly over the inclined surface 54 against the boss or projection 55 to lock the door D in closed 30 position. When the door is to be opened the latch 56 is raised and the door will swing outwardly and downwardly on its pivot pins 52. A knob or handle 58 is also provided at the upper edge of the door. 35 A cover plate 60 rests on projections 61 at the upper edge of the body H and these projections hold the cover plate 60 a slight distance above the upper edge of the body H to provide the outlets 62 for products of combustion. As shown in Fig. 10, the cover 40 plate 60 extends laterally farther to one side of the body H over the cut-out part 46 so as to form a deflector for the heat escaping through the opening 46. The cover plate 60 is also provided with an opening through 45 which the post 23 passes and supports the asbestos insulating plate 63. The asbestos plate 63 for which might be substituted an air space is held in place by an upwardly 50 extending rim flange 64 on the cover plate 60. A second plate 65 is provided with an opening to fit over the post 23 and fits within the rim flange 64 and seats upon the asbestos heat insulation 63. The second plate 65 is 55 provided with a plurality of knobs 681 on its upper side to space the handle plate 66 from the said second plate 65, but the space thus formed may be filled with insulating material. The air space 67 between the plates 60 and 66 is within the rim 68 which holds 60

the handle plate 66 in place. The handle plate has a handle 69 formed integral therewith and also has a depression 70 in its upper side which surrounds an opening 71 through which the upper end of the post 23 70 extends. The depression 70 is designed to receive the nut 72 which fits on the upper end of the post 23 and when screwed into place holds the hollow body H and the parts resting on it in place. Since the nut 72 is 75 counter-sunk a certain distance in the depression 70 there will be plenty of space beneath the horizontal part of the handle 69 to prevent a human hand, when grasping the handle, coming in contact with the upper 80 end of the post 23 which is apt to be quite hot.

The assembling and operation of my improved sad iron will be apparent from the foregoing description. While I have shown 85 and described my invention in detail it is to be understood that certain features thereof are of general application and therefore I do not wish to be limited to the exact form herein disclosed. 90

Having described the invention, what is claimed and desired to be secured by Letters Patent is:

1. A sad iron comprising a hollow body, a handle, a burner, a hollow base comprising a perforated floor plate for the body and an ironing plate, and a rib extending upwardly from the perforated floor plate within the sides of the body and below the burner, means for securing together in operative relation said hollow body, handle, 95 burner and base, 100

2. A sad iron comprising a hollow body, a handle, a burner, a partially hollow base comprising a perforated floor plate for the 105 body and an ironing plate, and a rib extending upwardly from the floor plate adjacent to the openings in said floor plate.

3. A sad iron comprising a hollow body, a handle, a burner, a hollow base including 110 a floor plate for the body and an ironing plate, heat conducting webs joining the ironing plate and the floor plate, an air channel between the webs, and two series or rows of openings through the floor plate 115 opening into said channel.

4. A sad iron comprising a hollow body, a handle, a burner, a partially hollow base comprising a floor plate for the body and an ironing plate, heat conducting webs joining the ironing plate to the floor plate, and an air passage formed between the outer extremities of said plates, the said air passage extending continuously from near the forward end of the sad iron to the rear or heel 120 thereof, means for securing together in operative relation said hollow body, handle, burner and base, 125

5. A sad iron comprising a hollow body, a handle, a burner, a partially hollow base 130

- comprising a floor plate for the body and also an ironing plate, heat conducting webs joining the ironing plate and the floor plate, a door provided with hinge pivots, and upwardly projecting lugs on the floor plate near the heel thereof to serve as retaining means for the hinge pivots, means for securing together in operative relation said hollow body, handle, burner and base.
10. 6. A sad iron comprising a hollow body, a handle, a burner, a partially hollow base comprising a floor plate for the body and an ironing plate, heat conducting webs joining the ironing plate to the floor plate, and a flange extending around the floor plate outwardly of the side of said body, means for securing together in operative relation said hollow body, handle, burner and base.
15. 7. A sad iron comprising a hollow body, a handle, a burner, a partially hollow base comprising a floor plate for the body and an ironing plate, heat conducting webs joining the ironing plate to the floor plate, a flange extending around the outer margin of the ironing plate, and ribs connecting said flange to the heat conducting webs, the heat conducting webs terminating a distance within said flange, means for securing together in operative relation said hollow body, handle, burner and base.
20. 8. A sad iron comprising a hollow body, a handle, a burner, a partially hollow base comprising a floor plate for the body and an ironing plate, heat conducting webs joining the ironing plate to the floor plate, and a plurality or series of air openings in the floor plate.
25. 9. A sad iron comprising a hollow body, a handle, an apertured floor plate, a burner having a series of downwardly directed outlets, and a wall extending upwardly from the floor plate toward the burner, said wall being located between the apertures in the floor plate and the burner outlets, means for securing together in operative relation said hollow body, handle, floor plate and burner.
30. 10. A sad iron comprising a hollow body, a handle, a heater, and a removable one-piece partially hollow combined floor plate and ironing plate, said plates being united and spaced apart by heat conducting webs, said floor plate being apertured and the edges between the floor plate and the ironing plate being spaced apart to provide means for admitting air into the space between said ironing plate and floor plate, means for securing together in operative relation said hollow body, handle, heater and combined floor plate and heating plate.
35. 11. A sad iron comprising a hollow body, a handle, a heating means, an ironing plate, an apertured floor plate, heat conducting webs uniting said plates, said ironing plate and floor plate having an open space therebetween at their edges to admit air, and channels between the heat conducting webs terminating in wide mouth openings at the air inlet space between the edges of said plates, means for securing together in operative relation said hollow body, handle, heating means, ironing plate and floor plate.
40. 12. A gas heated sad iron comprising a hollow body, a handle, a gas burner, an ironing plate, an apertured floor plate, heat conducting webs uniting said plates but spacing them apart to provide channels therebetween, one of said channels extending lengthwise of the ironing plate between said webs, and other channels leading laterally therefrom between the webs, said plates being spaced apart at their edges to provide an inlet for air, said lateral channels communicating with said air inlet space, means for securing together in operative relation said hollow body, handle, burner, ironing plate and floor plate.
45. 13. A sad iron comprising a hollow body, a handle, a burner, an apertured floor plate, an ironing plate, heat conducting webs uniting said plates but spacing them apart, a flange extending upwardly from the ironing plate at the edge thereof but terminating below said floor plate to leave a space for the admission of air, and walls on the floor plate connecting each of said heat conducting webs to the said flange to form separate passages for air leading from the edge of the sad iron to the center thereof, means for securing together in operative relation said hollow body, handle, burner, ironing plate and floor plate.
50. 14. A sad iron comprising a hollow body having side walls, an apertured rear wall and open at the top and bottom, a burner within said body, an ironing plate arranged below the body, and a handle attached to said body.
55. 15. A sad iron comprising a base, a hollow body mounted on said base, a handle, a burner disposed within said hollow body comprising a hollow chamber provided with an inlet and outlets for combustion material, and a flange extending from the burner toward the base between the outlets of the burner and the inner sides of the hollow body, means for securing together in operative relation said hollow body, handle, burner and base.
60. 16. In a sad iron, the combination of a base comprising an ironing plate, a floor plate, and heat conducting webs connecting said floor plate and ironing plate, a hollow body mounted on said base, a burner disposed within said hollow body, a handle plate, a handle carried by said handle plate, and fastening means having a part secured to said base and fastening said base, burner, hollow body, handle plate and handle together.
65. 17. In a sad iron, the combination of a

base comprising an ironing plate, a floor plate, and heat conducting webs uniting said floor plate and ironing plate, a hollow body mounted on said base, a handle plate, a handle carried by said handle plate, a burner within said hollow body, said handle plate and burner having openings extending therethrough, a post secured to said base and extending upwardly through the openings in said burner and handle plate, and means coöperating with said post to hold the handle plate, hollow body and burner in place on said base.

18. In a sad iron, the combination of a hollow base comprising an ironing plate, a floor plate, heat conducting webs uniting said floor plate and ironing plate but spacing them apart, said base having an inlet for admitting air into the space between said floor and ironing plates and said floor plate having air outlet apertures therein, a burner mounted on said floor plate above said apertures and having outlets for combustion material, and a wall on said floor plate extending upwardly therefrom and located between the apertures in the floor plate and the outlets in said burner.

19. In a sad iron, the combination of a hollow base comprising an ironing plate, a floor plate, heat conducting webs uniting said floor plate and ironing plate but spacing them apart, said base having an inlet for admitting air into the space between said floor and ironing plates and said floor plate having air outlet apertures therein, a burner mounted on the said floor plate above said apertures and having outlets for combustion material, a wall on said floor plate extending upwardly therefrom and located between the apertures in the floor plate and the outlets in said burner, and a flange extending downwardly from said burner toward said base and located outside the outlets of said burner.

20. In a sad iron, the combination of a base comprising a floor plate, an ironing plate, heat conducting webs uniting said floor plate and ironing plate but spacing them apart, means for admitting air to the

space between said floor and ironing plates, said floor plate having apertures therein near the longitudinal center thereof and also having walls on opposite sides of said apertures extending upwardly from the floor plate, the floor plate also having a groove formed in its upper side, a burner mounted on the upper side of the floor plate and spaced therefrom, said burner having a chamber therein provided with an inlet for combustion material and outlets in its bottom opposite the top side of the floor plate but on the outer side of said upwardly extending walls adjacent the apertures in the floor plate, a flange extending downwardly from the burner toward the floor plate and forming a flame chamber below said burner open at the rear and partially open at the sides, a hollow body inclosing said burner and flame chamber and being open at the top and bottom and also having a cutaway portion in the upper part of one of its side walls, the lower edge of said hollow body fitting in the groove in the upper side of said base, projections at the upper edges of said hollow body, a cover plate resting on said projections and having a part extending laterally over the cutaway part of the side of said hollow body, a plate of insulating material over said cover plate, a second plate over said insulating material, a handle plate mounted over the second plate and insulated therefrom by an air space, a handle carried by said handle plate, a depression in the upper side of said handle plate, a threaded post rigidly mounted on said base, said burner, cover plate, second plate and handle plate having openings therein through which said post extends, and means coöperating with said post to clamp the parts of the sad iron together.

21. A sad iron comprising a hollow body, a handle, a burner, the hollow body being open at the top and open at the bottom and open at the rear, and a movable closure for said rear opening.

In testimony whereof I affix my signature. 100
MONROE SUNSHINE.
